UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

ELECTROMAGNETIC DEVICE.

Application filed November 30, 1923. Serial No. 677,829.

This invention relates to electromagnetic devices suitable for loud speaking receivers, phonographic recorders and the like.

The object of the invention is to provide an electromagnetic system capable of translating electrical vibrations into acoustical or mechanical vibrations or vice versa with minimum distortion.

In accordance with one of its features, the invention provides an electromagnetic system so arranged that eddy current losses are induced in the vibratory member and utilized to dampen its vibrations, to prevent distortion in the vibrations produced. In general, this feature consists in the provision of a centrally supported closed coil of one turn carrying a steady current, each end of the coil being adapted to vibrate in a steady magnetic field.

The distortions are further reduced by providing a mounting for the coil resilient in the direction of normal movement of the coil but resistant to movement in other directions, this mounting consisting of supports of comparatively thin sheet metal having a plurality of radial vanes formed integral therewith by shearing sections and turning the sheared portions at right angles to the plane of the support.

Referring to the drawing, Fig. 1 is a perspective view of an electromagnetic device embodying this invention applied to loud speaking receivers embodying the invention.

Fig. 2 is an electromagnetic device embodying the invention adapted to recorders or reproducers.

Fig. 3 is a cross-sectional view of an electromagnetic device as shown in Fig. 1 showing the circuit diagrammatically.

Fig. 4 is an enlarged detail view showing the support for the vibratory member.

Fig. 5 is a section through the support.

Cores 5 and 6 which may be supported in a case (not shown) are E-shaped having arms 7, 8 and 9, and 10, 11 and 12, respectively. The middle arms 8 and 11 are provided with line coils 13 and 14, respectively. Supported between the cores 5 and 6 and insulated therefrom are members 15 and 16, provided with lugs 17 and 18, respectively, to which electrical connections may be made. The members 15 and 16 have spider-shaped portions 19 and 20, respectively intermediate their ends, the vanes being formed by shear-

ing the metal radially and turning the sheared portion at right angles to the plane of members 15 and 16, thereby providing radially extending vanes which are comparatively flexible in the plane of members 19 and 20 and rigid in planes at right angles thereto. To the centers of the spider portions are attached studs 21 and 22 carrying a closed circuit coil 23 of any light non-magnetic metal such as aluminum adapted to vibrate between the arms of the cores 5 and 6. One end of the coil 23 is provided with an extension 24 to which a diaphragm 26 may be connected by means of a link 25. In the modification shown in Fig. 2 a stylus holder 30 for a recording stylus 31 is mounted directly on the coil 23.

In the preferred embodiment of the invention the vibratory coil 23 is connected through its supports to a source of energy 32 which provides a steady current in opposite directions through each section of the coil 23. The coils 13 and 14 are connected in series with the secondary of the transformer 35 and hence the alternating current induced in them by means of a translating device 34 with its energy source 33 produces forces which tend to make the coil 23 vibrate. A source of energy 36 is connected between the middle point of the secondary and the common terminal between the coils 13 and 14 providing a steady current in coil 13 opposite to that in coil 14. The polarity of the core 5 due to the steady current is therefore opposite to that of the core 6, and hence when coil 23 vibrates E. M. F.'s in the same direction are set up in its two halves by this flux which produce damping currents. The E. M. F.'s due to the vibration of coil 23 in the alternating fields are in opposite directions and hence do not set up damping currents.

Obviously separate coils may be placed upon the cores 5 and 6 for the steady current instead of using the push-pull circuit shown.

What is claimed is:

1. An electromagnetic system for producing distortionless vibrations comprising an electromagnet providing a variable magnetic field, a coil movable in and transverse said field and a source of steady current for said coil.
2. An electromagnetic system for produc-

- ing distortionless vibrations comprising a magnet, a movable short-circuited coil in the field of said magnet, and a source of steady current for said coil.
5. An electromagnetic system for producing distortionless vibrations comprising an electromagnet, a movable short-circuited coil disposed in the field of said magnet, means for supporting said coil whereby it 10 may oscillate about an axis in the plane of said coil, a source of steady current for said coil, the current flowing in the opposite directions from the axis through said coil.
4. An electromagnetic system for producing distortionless vibrations comprising a pair of electromagnets, a centrally supported movable coil, one end of which is in the field of one magnet and the opposite end in the field of a second magnet, a source of 15 steady current, and means whereby the current is supplied to the opposite ends of the coil in parallel.
5. In an electromagnetic device, a short-circuited coil of non-magnetic material, a resilient support for said coil the axis of support lying in the plane of the coil, and elec- 20
- 25
- tromagnets associated with the opposite ends of said coil.
6. In an electromagnetic device, a pair of spaced E-shaped electromagnets, a short-circuited coil of non-magnetic material resiliently supported at its center between said magnets and insulated therefrom, one end of said coil being in the field of one magnet, and the other end in the field of the other magnet. 30
7. In an electromagnetic device a magnet providing a variable magnetic field, a short-circuited coil disposed in said field, and means for movably supporting said coil. 40
8. In an electromagnetic device, a vibratory short-circuited coil, of one turn, a source of energy supplying a steady current in opposite directions through parts of said coil electromagnets in operative relation to each part of said coil, and means providing a steady and a variable magnetic field in 45 said magnets.

In witness whereof, I hereunto subscribe my name this 21st day of November A. D., 50 1923.

HENRY C. HARRISON.
